UNITED STATES PATENT OFFICE

EDWARD H. HAZEN AND SAMUEL L. LEVI, OF NEW YORK, N. Y.

HORSESHOE.

1,227,133.

Specification of Letters Patent. Patented May 22, 1917.

Application filed November 12, 1913. Serial No. 800,567.

To all whom it may concern:

Be it known that we, EDWARD H. HAZEN, a citizen of the United States of America, and resident of New York, in the county and State of New York, and SAMUEL L. LEVI, a citizen of the United States, and resident of New York, in the county and State of New York, have invented a certain new and useful Improvement in Horseshoes, 10 of which the following is a specification.

This invention broadly relates to horseshoes, and more particularly contemplates the provision of a device adapted for use auxiliary to an ordinary horse-shoe, there- 15 by to increase the road-gripping efficiency of the latter.

An object of the invention is to provide a calk and a seat or mounting therefor, which, preferably in combination with an 20 auxiliary wedge element or equivalent, will permit of the ready detachability of the calk, and with greater convenience and despatch than have been possible heretofore.

Another object is to provide a device as 25 above described, and one which, in addition to supporting the calk or calks present in an exceedingly simple manner, will positively prevent the accidental loss or displacement of any or all thereof.

30 Other objects and aims of the invention, more or less broad than those stated above, together with the advantages inherent, will be in part obvious and in part specifically referred to in the course of the following 35 description of the elements, combinations, arrangements of parts, and applications of principles constituting the invention; and the scope of protection contemplated will appear from the claims.

40 In the accompanying drawing, which is to be taken as a part of this specification, and in which there is shown one of the many possible embodiments of the invention as at present preferred:

45 Figure 1 is a top plan view of one of said embodiments, as assembled and mounted upon the horse-shoe 6 shown in dotted lines;

50 Fig. 2 is a side elevation of one of the two side-sections 7, which, in the present instance, constitute the main structure of an auxiliary overshoe adapted to carry any suitable plurality of calks and adapted to be readily mounted upon or dismounted 55 from said ordinary horse-shoe 6, the lugs 8,

however, being shown as not yet bent over upon themselves as disclosed in Fig. 1;

Fig. 3 is a transverse sectional view, taken on the line 3—3 of Fig. 1;

Fig. 4 is a view similar to Fig. 3, but 60 taken on the line 4—4 of Fig. 1; and

Fig. 5 illustrates a slightly different construction, and one wherein a lug 8 is shown as being integrally carried by one of the calks 14, the horse shoe proper being indicated at 6, and one of the side sections of the overshoe being indicated at 7.

Similar reference characters refer to similar parts throughout the several views of the drawing.

Inasmuch as it is believed that the disclosure of an illustrative application of this invention in connection with the provision of an auxiliary overshoe will best secure the objects and advantages herein set forth and apparent, and referring now particularly to Figs. 1, 2, 3 and 4 of the drawing, an ordinary horse-shoe is delineated at 6, in dotted lines in Fig. 1 and in full lines in Figs. 3 and 4.

The overshoe structure here provided and adapted for removable attachment to said shoe 6 includes the substantially similar and symmetrically arranged opposed side-sections 7. Each section is provided with a 85 central horizontally extending and offset extension 9 as shown, each extension terminating in an upturned vertical lip 10. Lips 10 are suitably transversely apertured, and these apertures are provided with right and left threads, respectively, so that with sections 7 opposed as disclosed in Fig. 1 and with the correspondingly threaded ends of the single screw 11 each coöperating with 90 one of said threaded apertures, said screw 95 may be turned in one direction or the other to draw together or urge apart said sections 7. Screw 11 carries a nut 12 fixedly thereon, and a nut 13 loosely thereon; the former for utilization in turning the screw 11 and the latter for clamping said screw against rotation after it has been predeterminedly adjusted.

Each section 7 carries in a manner now to be described a plurality of road-engaging elements, as the calks 14. The shank of each of the calks 14 illustrated in Figs. 3 and 4, is shown as including two parallel and vertical walls 15 and 16 (Fig. 3), and two substantially parallel but inclined walls 110

17 and 18 (Fig. 4). The shank of each of these just mentioned calks 14, together with a wedge 19, is here adapted to be accommodated (Fig. 1) within one of a plurality of 5 the transverse slots illustrated as formed in the sections 7. Each transverse slot (as will be seen from Fig. 1) has four side walls, two of these walls (as will be seen from Fig. 3) being oppositely disposed and adapted 10 to abut respectively the walls 15 and 16 of a calk shank, and the other two of these walls (as will be seen from Fig. 4) being oppositely disposed and adapted one to abut the wall 17 of a calk-shank and the other 15 to abut the wedge 19 and thus indirectly bear against the wall 18 of the calk-shank. The dimensions and relations of a slot and its associated calk-shank are such that with the wedge 19 entirely removed from the slot, 20 the free end of the shank is insertible into the slot in the direction of the arrows 20 one disclosed in Fig. 3 and the other disclosed in Fig. 4. During the process of thus inserting the calk-shank, the wall 18 there- 25 of will preferably and usually travel upward in substantial adjacency to the wall of the slot which in Fig. 4 is shown as in abutment with the wedge 19. Immediately thereafter the calk is rocked in the direction of the arrow 21 to bring the wall 17 30 of the calk shank into abutment with the wall of the slot which is shown in Fig. 4 as being in abutment with said wall 17. The wedge 19 is then inserted in the direction of the arrows 22 disclosed in Figs. 3 35 and 4, the design of said wedge being such that when it is so forced home it will, as illustrated in Fig. 4 and in an obvious manner, lock the calk against displacement in 40 the direction of the arrows 22 before the sections 7 are mounted upon the shoe 6 and lock the calk against displacement in any direction after the sections 7 are mounted upon said shoe.

45 The wedge 19 shown in section in Fig. 4 may be located at 19' in Fig. 3, being bounded by the dotted line 23, the full-line 24 and the calk-shank walls 15 and 16. The dotted line 25 represents the under surface 50 of a section 7 as well as the joining line between the calk and its shank. It will be seen from Figs. 3 and 4 that the wedge is not as long as the calk-shank; but the lower edge of the wedge, instead of resting on an uninterrupted ledge located within the associated slot, is here supported against accidental displacement in the direction of the arrow 22 by means of its abutment with a pair of spaced ears 26 (one of which is 55 shown in full lines in Fig. 4 and both of which are shown in dotted lines in Fig. 3). Coöoperating with wall 18 of the calk shank (Fig. 4), said wall being prolonged into a groove 27 (shown in dotted lines in Fig. 60 3 and in full lines in Fig. 4), the ears 26

establish an upwardly extending passage through which may be inserted a wedge-ejecting tool of any desired type. This construction renders exceedingly expeditious and convenient the ejection of a wedge 19, 70 especially with the sections 7, or after they have been dismounted from the shoe 6; it being merely necessary to insert said tool into the groove 27 and then drive the tool sufficiently in the direction of the arrow 20 75 to cause said tool to pass the ears 26 and thereafter force from within the slot the wedge 19. It is quite obvious, on the other hand, that with the wedge 19 properly in place, and the sections 7 mounted upon the 80 shoe 6 as hereinafter described, it will be utterly impossible to accidentally eject a wedge 19 and thus render a calk 14 free to drop from its slot.

As to the method of mounting sections 85 7 upon the shoe 6, attention is first called to the upstanding lugs 8 in Fig. 2. The sections 7 are preferably in practice carried upon the underside of the shoe and the lugs 8 are bent over upon themselves as disclosed in Figs. 1, 3 and 4 so that the vertical portions of the lugs may embrace the outer side edges of the shoe 6 and the horizontal portions of said lugs may engage with the upper face of said shoe, the general relation 90 of the parts being best indicated in Fig. 1. The lugs 8 may be thus bent upon themselves before or after initially mounting the sections 7 upon the shoe 6, the dimensions of the vertical portions of the lugs in any event 100 95 preferably being such that the proper grip may be given to any of the ordinary horse-shoes of varying thicknesses. The lugs 8 having been so bent, the side sections are drawn together to mount the entire structure here illustrated upon the horse-shoe 6, 105 in an obvious manner and by a preliminary adjusting manipulation of the nut 12 and a final and clamping adjustment of the nut 13.

Attention is called to the disclosure in Figs. 3 and 4 of the substantially continuous bead or tenon 29 carried by a section 7, which, if desired, may be utilized in connection with a coöoperating substantially 115 continuous groove or channel 30 carried by a calk 14, the tenon and the groove being adapted in an obvious manner to diminish the torsional stress which would otherwise in practice be at times put upon the calk-shank.

Referring now particularly to Fig. 5, a modification of the embodiment described above is disclosed. Here the sections 7 and the shoe 6 are shown as being locked together by means of a preferably integral structure which includes a calk 14, a calk-shank 14' (this calk-shank being accommodated in a suitable slot carried by the section 7) and a bent over lug 8. Each sec- 120 125 130

tion 7 may carry an extension 9 similar to the extension 9 shown in Fig. 1, so that with the lug 8 bent over as shown, any adjusting device associated with the extension 9, such as the screw 11 shown in Fig. 1, may be manipulated either to draw the sections 7 in the direction of the arrow 31, to temporarily lock in place the calk 14, or to force the sections 7 in the direction of the arrow 32 to render the calk 14 and its integral structure instantly removable and, if desired, replaceable by another calk structure of substantially the same type.

It will thus be seen that we have provided an embodiment of this invention well calculated as aforesaid to attain the various ends and objects thereof, and one, moreover, having important advantages of simplicity, economy, efficiency and ease of manipulation.

Inasmuch as many changes could be made in the above construction, and many apparently widely different embodiments of our invention could be made without departing from the scope thereof, it is intended that all matter contained in the above description or shown in the accompanying drawing shall be interpreted as illustrative and not in a limiting sense.

It is also to be understood that the language used in the following claims is intended to cover all the generic and specific features of the invention herein described and all statements of the scope of the invention which, as a matter of language, might be said to fall therebetween.

Having described our invention, what we claim as new and desire to secure by Letters Patent, is:

1. In a device of the kind described, in combination, a calk-carrying member having an opening extending therethrough, a calk having a shank adapted to be inserted upwardly into said opening, and a wedge piece adapted to be inserted downwardly into said opening between the wall of the opening and the calk shank, said wedge piece having a length not greater than the

distance from one side of said opening to the other, and when in wedging relation with the calk shank extending substantially to the outer end of said opening and not beyond the same.

2. In a device of the kind described, in combination, a calk-carrying member having an opening extending therethrough, a calk having a shank adapted to be inserted upwardly into said opening, and a wedge piece adapted to be inserted downwardly into said opening between the wall of the opening and the calk shank, said wedge piece having a length not greater than the distance from one side of said opening to the other, and when in wedging relation with the calk shank extending substantially to the outer end of said opening and not beyond the same, said calk being cut away to afford access to the outer end of the wedge piece.

3. In a device of the kind described, in combination, a calk-carrying member having an opening extending therethrough, a calk having a shank adapted to be inserted upwardly into said opening, and a wedge piece adapted to be inserted downwardly into said opening between the wall of the opening and the calk shank, said wedge piece having a length not greater than the distance from one side of said opening to the other, and when in wedging relation with the calk shank extending substantially to the outer end of said opening and not beyond the same, said calk being cut away to afford access to the outer end of the wedge piece, the portions of the calk about said cut-out portion bearing against the said member beyond said opening.

In witness whereof we have hereunto signed our names in the presence of two witnesses.

EDWARD H. HAZEN.
SAMUEL L. LEVI.
